UNITED STATES PATENT OFFICE.

PAUL R. FORTIN, OF SCHENECTADY, NEW YORK, ASSIGNOR TO GENERAL ELECTRIC COMPANY, A CORPORATION OF NEW YORK.

ELECTRICAL CONNECTER.

Application filed October 19, 1921. Serial No. 503,655.

My present invention relates to electrical connectors, particularly to connectors of the type which may be readily attached and detached from a conductor.

- 5 One of the objects of my invention is to provide a simple and efficient connector for making an electrical connection between two conductors whereby a tightening of a single member will simultaneously secure both conductors to be connected to the connecting device. A further object of my invention is to provide such a device which will be adapted to connect two conductors of different size or cross-section.
- 10 13 The novel features which I believe to be characteristic of my invention are set forth with particularity in the appended claims, my invention itself, however, both as to its organization and method of operation will 20 best be understood by reference to the following description taken in connection with the accompanying drawing in which Fig. 1 is a perspective view of my improved connector, indicating the manner in which the 25 two different conductors are joined; Fig. 2 is a side elevation of my connector, and Fig. 3 is a cross-section of the connector.

As indicated in the drawing, the connector comprises two bifurcated portions or jaw members 1 and 2 which are substantially parallel to each other. These parallel portions are connected by two diverging portions 3 and 4 and an intermediate portion 5, which extends at substantially right angles to the members 1 and 2. A bolt 6 which together with thumb nut 7 forms a binding post, extends through an opening in the intermediate portion 5 of the connector. This bolt has a T-shaped head 8 which is inserted in the bifurcations of the two jaw members 1 and 2. The head 8 of the bolt is provided with inclined surfaces 9 and 10, which coact with the diverging portions 3 and 4 of the connector so that when the thumb nut 7 is tightened to secure the conductor 11 to the connector the jaw members 1 and 2 are pressed toward each other. As a result these jaw members are caused to grip the conductor 12 which is interposed between them. In 40 other words, by tightening the thumb nut 7 the conductors 11 and 12 are simultaneously secured to the connector. I have indicated the conductor 11 as a flat braided conductor which is secured to a terminal 13, this terminal being preferably merely

pinched upon the conductor to secure it thereto. The terminal 13 is flared outwardly at 14 and this outwardly flared portion 14 prevents the terminal from rotating when the thumb nut 7 is tightened.

While I have illustrated my invention as employed for connecting a comparatively small wire with a flat conductor of larger cross-section, it is apparent that by suitable modification of the shape of different portions of the connector, it may be adapted to form a reliable electrical connection between two conductors of any shape or cross-section desired without departing from the scope of my invention as set forth in the appended claims.

What I claim as new and desire to secure by Letters Patent of the United States, is:—

1. An electrical connector comprising a gripping member having two substantially

parallel portions directly opposite each other, two diverging portions and a portion connecting said diverging portions, and a bolt extending through said connecting portion for securing an electrical conductor thereto, the head of said bolt being adapted to bear against said diverging portions and thereby press the parallel portions toward each other to cause them to grip an interposed conductor.

2. An electrical connector comprising a gripping member having two substantially parallel bifurcated portions, two diverging portions and a portion connecting said diverging portions and a T-headed bolt extending through said connecting portion, the head of said bolt being adapted to coact with the diverging portions and thereby press the parallel portions toward each other to cause them to grip an interposed conductor.

3. An electrical connector comprising a gripping member having two substantially parallel bifurcated portions, two diverging portions and a portion connecting said diverging portions and a T-headed bolt extending through said connecting portion, the head of said bolt being inserted in the bifurcations of said parallel members and being adapted to coact with the diverging portions of the gripping member to press the parallel portions toward each other to cause them to grip an interposed conductor.

4. An electrical connector comprising a gripping member having two substantially

- parallel bifurcated portions, two diverging portions and a portion connecting said diverging portions and a **T**-headed bolt extending through said connecting portion, 5 the head of said bolt being adapted to coact with the diverging portions to press the parallel portions toward each other to cause them to grip an interposed conductor, said bolt also serving as a binding post for securing a conductor to said gripping member.
5. An electrical connector comprising a pair of opposing bifurcated jaw members, an intermediate member connecting said jaw members and a **T**-headed bolt extending 10 through said intermediate member, the head of said bolt being adapted to exert a pressure 15 sure for pressing said jaw members together to grip an interposed conductor.
6. An electrical connector comprising a pair of opposing bifurcated jaw members, 20 an intermediate member connecting said jaw members and a **T**-headed bolt extending through said intermediate member, the head of said bolt being inserted in the bifurcations of said jaw members and being adapted 25 to exert a pressure for pressing said jaw members together to grip an interposed conductor.

In witness whereof, I have hereunto set my hand this 18th day of October, 1921.

PAUL R. FORTIN.
